(57) **CLAIM**

We claim the ornamental design for a paint applicator handle, as shown and described.

DESCRIPTION

This application is related to U.S. patent application Ser. No. 29/153,826 entitled Paint Applicator Handle filed on Jan. 11, 2002 by Matthew G. Goulet originally including 25 figures, the full disclosure of which is hereby incorporated by reference, U.S. patent application Ser. No. 29/153,825 entitled Paint Applicator Handle filed Jan. 11, 2002 by Mathew G. Goulet including 27 figures, the full disclosure of which is hereby incorporated by reference, and U.S. Design patent application Ser. No. 29/153,851, entitled "Paint Applicator Handle", filed on Jan. 11, 2002, by Mathew G. Goulet, the full disclosure of which is hereby incorporated by reference.

FIG. 1 is a perspective view of a paint applicator handle of the present invention;

FIG. 2 is a top plan view thereof, the bottom plan view being a mirror image of the top plan view;

FIG. 3 is a rear elevational view thereof;

FIG. 4 is a front elevational view thereof;

FIG. 5 is a left end elevational view thereof;

FIG. 6 is a right end elevational view thereof;

FIG. 7 is a perspective view of a first alternative embodiment of the paint applicator handle of FIG. 1;

FIG. 8 is a top plan view thereof, the bottom plan view being a mirror image of the top plan view shown;

FIG. 9 is a rear elevational view thereof;
FIG. 10 is a front elevational view thereof;
FIG. 11 is a left end elevational view thereof;
FIG. 12 is a right end elevational view thereof;
FIG. 13 is a perspective view of a second alternative embodiment of the paint applicator handle of FIG. 1;
FIG. 14 is a top plan view thereof, the bottom plan view being a mirror image of the top plan view shown;
FIG. 15 is a rear end elevational view thereof;
FIG. 16 is a front end elevational view thereof;
FIG. 17 is a left end elevational view thereof;
FIG. 18 is a right end elevational view thereof;
FIG. 19 is a perspective view of a third alternative embodiment of the paint applicator handle of FIG. 1;
FIG. 20 is a top plan view thereof;
FIG. 21 is a rear elevational view thereof;
FIG. 22 is a bottom plan view thereof;
FIG. 23 is a front elevational view thereof;
FIG. 24 is a right end elevational view thereof;
FIG. 25 is a left end elevational view thereof;
FIG. 26 is a perspective view of a fourth alternative embodiment of the paint applicator handle of FIG. 1;
FIG. 27 is a top plan view thereof;
FIG. 28 is a rear elevational view thereof;
FIG. 29 is a bottom plan view thereof;
FIG. 30 is a front elevational view thereof;
FIG. 31 is a right end elevational view thereof; and,
FIG. 32 is a left end elevational view thereof.

The broken lines immediately adjacent the shaded portions represent the bounds of the claimed design and all other broken lines are for illustrative purposes only. None of the broken lines form part of the claimed design. The surface shading represents a contrast in color, texture, or materials and does not indicate a specific color or surface characteristic.
